EXHAUSTING MACHINE

Anthony J. Marshau, Cleveland, Ohio, assignor
to General Electric Company, a corporation of
New York

Application November 9, 1939, Serial No. 303,639

8 Claims. (Cl. 176—2)

My invention relates to the manufacture of sealed electric lamps, discharge devices and the like, and more particularly to apparatus for exhausting, gas filling and then sealing such devices.

Electric discharge devices are exceedingly difficult to exhaust completely of the many forms of contaminating substances that are held by the various parts thereof and which otherwise would pass into the interior atmosphere of the devices sometime during the life thereof. The contaminating substances are held very tenaciously but can be dislodged and drawn off during exhaust if the device is heated to a high temperature and a discharge is supported during this operation. One object of my invention is to provide apparatus for automatically bringing about these and other exhaust operations in the form of a high production machine to allow the economical manufacture of devices of this type. Another object of my invention is to provide exhaust apparatus of suitable size and construction to handle elongated tubular light producing discharge devices, as well as similar forms of incandescent lamps. Long tubular devices are 25 too cumbersome to be handled in the usual manner and are so heavy as to require more support than is provided by the mere engagement of the exhaust tube with the exhaust port, as is common in the manufacture of ordinary incandescent lamps.

The introduction of a vaporizable metal, such as mercury, required in many discharge devices presents other difficulties, and another object of my invention is to provide apparatus in combination with the above type exhausting apparatus for introducing the vaporizable material into said devices. Since it is not possible to introduce the vaporizable material into such devices in the open air and then cause them to be exhausted, the exhaust port is preferably arranged in an inverted position with the exhaust tube of the discharge device inserted from below, and a suitable dispenser, preferably of the type disclosed in my application Serial No. 223,519, filed August 16, 1938, is mounted thereon in such a manner that the vaporizable material falls by gravity through the exhaust port and into the discharge device.

Another object of my invention is to provide suitable apparatus for sealing or tipping off the exhaust tube after the exhausting and gas filling operations while the device is still held by the apparatus comprising my invention. Other objects and advantages of my invention will ap-

pear from the following detailed description of a species thereof and from the accompanying drawings.

In the drawings, Fig. 1 is a plan view of exhaust apparatus comprising my invention with various portions broken away to show the underlying portions; Fig. 2 is a vertical section through the apparatus along line 2—2 of Fig. 1 with an intermediate portion of uniform construction removed therefrom; Fig. 3 is a front elevation of one of the heads of said apparatus; Fig. 4 is an end elevation of an oven for overall heating of a discharge device; Fig. 5 is a diagrammatic perspective view of certain actuating mechanisms; Fig. 6 is an end view of mechanism for making electrical connections to a discharge device; Fig. 7 is a side elevation of actuating means for a mercury dispenser; Figs. 8 and 9 are plan and side views of exhaust tube tipping-off means, the latter figure also showing the end of a discharge device in operative relation therewith and an end view of an oven for heating the exhaust tube and adjacent end of said discharge device; and Fig. 10 is an end elevation of the tipping-off means on a larger scale and in operative relation to the discharge device shown in section.

Referring to Fig. 1, the apparatus shown comprises a plurality (thirty-two) of heads 15 which are mounted at regular spaced intervals about the periphery of a turret 16 and are advanced in turn through a similar number of stations by counter-clockwise indexing movements of the turret. Each head 15 is adapted to accommodate a single discharge device 17 as shown in Figs. 2 and 3 and, during the movement through said stations, carries said device through the various steps of the cycle of operation. In this particular instance, the discharge device 17 to be treated is a hot cathode discharge lamp having a relatively long tubular vitreous envelope 18 with a fluorescent coating on the inside and the hot cathode assemblies or mounts 19 sealed in each end. The discharge device 17 is completely sealed except for the vitreous exhaust tube 20 extending from one end and is introduced into the head 15 at one of the stations A, B or C.

Introducing a discharge device 17 into a head 15 consists in first separating the pairs of jaws 21—22 and 21'—22' and, after the envelope 18 has been gripped therebetween, in moving said discharge device upward through said jaws until the exhaust tube 20 is carried into the exhaust port 23. The jaws function as holding means

for the discharge device 17, the jaws 21—21' of each pair being fastened directly to the hollow post or sleeve 24 mounted on the arm 25 extending from the turret 16. Jaw 22 merely pivots on the hollow post 24 and is operated from Jaw 22' to which it is connected by the rod 26, whereas jaw 22' is fastened to the rod 27 extending upward through the hollow post 24. In opening the jaws, manual pressure is applied to the arm 28 on the upper end of the rod 27 to counteract the closing force of the helical torsion spring 29 extending between said arm 28 and the nut 30 on the upper end of the hollow post 24. The spring 29 also forces the rod 27 upward so that it is held in position.

The exhaust port 23 into which the exhaust tube 20 is pushed comprises a rubber washer 31, a head 32 in which said washer 31 is located, and a bracket 33 which is attached to the turret 16 and the head 32. In inserting the exhaust tube 20 in the port 23, it is pushed upward through the openings in the guide washer 34 and the rubber washer 31 until its end butts against the head 32, at which time the opening in said exhaust tube 20 is aligned with the axial passage 35 in said head 32. The function of the rubber washer 31 is to seal the exhaust tube 20 in the head 32 and the rubber washer 31 is compressed to seal off the opening. The only other duty of the operator is to pull the leading-in wires 38—38' extending from the cathode assemblies 19 at both ends of the envelope 18 so that they extend outward from the device 17 toward the front and back of the head 15 respectively.

The succeeding indexing movement of the turret 16 which carries the head 15 into station D brings about the first operation in the exhaust cycle as said motion adjusts the rotary valve 39 under the center of the turret 16 so that the proper exhaust connections are made to the port 23. The rotary valve 39 (Fig. 2) consists of upper and lower sections 40 and 41 respectively, and the rotation of the turret 16, which is connected to the upper section 40 through the pin 42, causes said upper section to turn on the stationary lower section 41 which rests on a raised center portion 43 of the frame and is kept in position thereon by the stud 44. The connection to the exhausting means (not shown) is made to the lower section 41 of the rotary valve 39 at 45, and a connecting passage 46 therein is now aligned with the passage 47 in the upper section 40 of said valve 39 which is connected through the pipe 48, the transparent (glass) trap 49, the pipe 50, the connection block 51 and the rubber tube 52 to the head 32 of the exhaust port 23. A spring 53 surrounding the pin 42 presses the upper and lower sections 40 and 41 of the rotary valve 39 together so that there is no leakage. The exhaust connection from the upper valve section 40 to the exhaust port 23 is complete at all times, and should a lamp 17 be left out of said port 23 as it leaves the loading stations, the operator can pinch off the connection by turning the cam 54 (Figs. 1 and 3) so that the intermediate body 55 is pushed against the rubber tube 52 which is thereby flattened. The cam 54 and the body 55 are located in a slot in the bracket 33 and are pivotally attached thereto. Alternate exhaust ports 23 are connected to the rotary valve 39 at the differently situated points 56 and a corre-

spondingly positioned connection as at 57 is provided for the exhaust connection.

The exhausting operation started at station D is continued at station E due to an exhaust connection made through the rotary valve 39, and is now assisted by the heating action of the arcuate oven 60 which surrounds the device 17 at this station. The oven 60 is mounted on the frame in the path of movement of the device 17 which is carried through an opening in the end of the oven 60 normally closed, as shown, by the door 61. The door 61 as shown in Fig. 4 is provided with grooved rollers 62 which ride on the track 63 and is slid back away from the oven 60 opening during indexing periods by movement of the arms 64 on rod 65 which are connected to said door 61 through the links 66 and brackets 67. The rod 65 is held by the brackets 68 extending from the oven supporting structure and is turned by means engaging the cam 69 on the main drive shaft 70 shown in Fig. 5. The cam 69 is engaged by the roller 71 on one end of the lever 72 which is pivoted on the pin 73 extending from the frame and which shifts the bar 74 (Figs. 1 and 5) longitudinally. The end of the bar 74 away from the lever 72 is held slidably by the bracket 75 on the frame and engages the arm 76 on the lower end of the rod 65 through the pin 77. A slot in the arm 76 accommodates the pin 77 and allows for the difference in the directions of movement thereof. An overhanging lip 78 on the top edge of the oven 60 keeps the upper portion of the door 61 thereagainst and forms a channel in which said door 61 is moved.

The only other opening in the oven 60 is a slot

in the top through which the exhaust tube 20 and the hollow post 24 extend. The side walls of

the oven 60 are insulated by the mineral wool

packing 79 and support the insulation buttons

80 on which the resistance wire 81 of the heater

is wound in zigzag fashion.

If some form of leak detecting means is to be used with this apparatus, it is preferred that it be coupled to the exhaust connection on the lower section 41 of the rotary valve 39 leading to the exhaust port 23 at this station E. The leak detecting means can be used either to close off the pinch clamp automatically or to give an alarm so that it can be closed off manually. If the exhaust ports 23 at stations D and E, or other stations, are connected to the same exhaust means, the leak detecting means can also be arranged to close off the exhaust connection to the exhaust port 23 at station E as soon as it is discovered so that there is little leakage which can interfere with the exhausting operations at the other stations.

In each of the succeeding stations up to station F, the exhaust operation is continued in the same manner as at the preceding stations. In each of these stations, the exhaust source is under the control of the rotary valve 39 and exhausting is carried on while the device 17 remains in the oven 60 and is heated, preferably to a temperature near the softening point of the envelope 18. The oven 60 does not extend to station F and, during the indexing movement to said station, the device 17 passes through an opening therein which is normally covered by a door (not shown). Said door corresponds to that provided at the opposite end of the oven 60 and is actuated in the same manner by a rod 82 connecting lever 72 (Fig. 5) and the arm 76' of the actuating means therefor.

The exhausting operation is continued at sta-

tion F and the succeeding series of stations and it is not until station G is reached that any other additional operation is performed. In moving to station G, the leads 38—38' connected to the ends of the coiled filamentary cathodes 83 of the assemblies 19 at both ends of the discharge device 17 wipe against the metal contact plates 84 located in their paths of movement, as shown in Fig. 6. The plates 84 serve to make electrical connections to the cathodes 83 which permit them to be heated and the materials, such as barium carbonate, carried by the cathode assemblies to be changed to oxides having the desired electron emissive properties. The contact plates 84 at station G correspond to other contact plates 84 at the seven following stations all of which are fastened at one end to one of the four bands 85 of insulation extending around the path of movement. The insulating bands 85 are attached to metal bands 86 which are located behind said insulating bands and are held in place by the rods 87 extending upward from the frame and engaging said metal bands 86 through the brackets 88. At station G and the three following stations, the electrical connections to the cathodes 83 are only those required to heat them and there is no difference in potential between the cathodes 83 at opposite ends of the device 17. At station H, the next in order, it is preferred that no connections be made to the plates 84 at all.

Before the discharge device 17 leaves station H, however, the dispenser 90 mounted on top of the exhaust port 23 is caused to discharge a drop of mercury which falls down through the exhaust passage of said port 23 and into the discharge device 17. The purpose of the mercury drop is to create a vapor within the device 17 which will support a local electrical discharge across portions of each of the electrodes or between their leads 38—38' and a main discharge from one cathode to the other to dislodge any other contaminating materials which may still remain in the other parts of the cathode assemblies 19 and cause activation of the remaining electron emissive material on said parts.

The dispenser 90 is preferably constructed as disclosed in my pending application referred to above. The said dispenser at this time is actuated by means of the solenoid 91 (Figs. 1 and 7) which is first moved down over the bell housing 92 thereof and is then energized. The solenoid 91 is mounted on the extending end of the arm 93 of insulating material attached to the upper end of the rod 94 which in turn is located in the hollow standard 95 (only partially shown) extending upward from the frame, and is moved vertically by the motion imparted to said rod 94 through motion of cam 96 (Fig. 5). The rod 94 is connected by the links 97 to the lever 98 which is pivoted on a pin extending from the frame and engages the cam 96 through the roller 99. During the downward movement of the rod 94, metal pins 100 mounted on the insulated block 101 carried by said rod 94 and connected to the leads of the solenoid 91 are carried into engagement with the connection means 102 mounted on the hollow standard 95 which in turn are connected through the switch 103 (Fig. 1) and switch 104 (Fig. 5) to a source of electric current.

The switch 103 limits the operation of the dispenser 90 to times when the exhaust port 23 is functioning properly as indicated by the position of the pinch-clamp closing cam 54. When the pinch clamp is open, the cam 54 engages the insulating body 105 on the end of the contact

5 arm 106 causing it to bend and engage the contact arm 107. Both contact arms 106 and 107 are mounted on a block of insulating material on the arm 108 extending from the standard 95. When the solenoid 91 is to be energized and the dispenser operated, the cam 109 actuates the switch 104 which completes the connections from the solenoid 91 to the source of electrical energy.

10 The magnetic field generated by the solenoid 91 penetrates the aluminum bell housing 92 and raises the magnetic armature 110 (Fig. 2) and the tubular plunger 111 attached thereto so that the opening 112 in said plunger 111 containing the measured amount of mercury from the pool 113 in the cup 114 is carried above the end of the discharge tube 115. The float 116 on the mercury pool 113 seals off the outer end of the opening 112 when it leaves said pool 113 and the jar occurring as the armature 110 strikes the top of the bell housing 92 dislodges the mercury causing it to fall down into the discharge tube 115. The weight of the mercury alone is sufficient to carry it down through the tube 115, the passage 117 in the cup 114 and the exhaust 20 passages in the connection block 51, the rubber tube 52, the head 32 and the exhaust tube 20 which deposits it in the interior of the device 17. After the dispenser 90 has been operated, the rod 94 and solenoid 91 are moved upward away from 25 operating relation therewith and the electrical circuit to said solenoid 91 is broken by movement of the pins 100 from contact with the connection means 102. The switch 104 breaks the circuit at some later time, depending on the cam 109, and only controls the discharge time of the dispenser 30 90. When the circuit to the solenoid 91 is broken first, the weight of the armature 110 moves the tubular plunger 111 down into the mercury pool 113 so that another charge thereof flows into 35 the opening 112 therein. The nut 118 screws onto the upper end of the cup 114 and presses the flange of the bell housing 92 thereagainst so that the interior of both said cup and housing is 40 sealed off from the atmosphere.

45 At the station following station H, the cathodes 83 are heated to full operating temperature and, at the next two stations, said cathodes 83 are again heated while full operating potential is applied thereto. The electrical connections for 50 these conditions are applied through the plates 84 which engage the leads 38—38' of the device 17 and result in a local discharge between portions of the leads 38—38' within the envelope and other portions of the cathodes 83 at all 55 three stations, and a steady discharge through the device at the two latter stations even though the device is being exhausted as before. The local discharge serves to activate the electron emissive material on the inner portion of the leads 38—38' and the other portions of the cathodes 83 and, together with the major discharge from end to end of the device, rids said device of any remaining contaminating materials. In some instances, the current applied to 60 the cathodes 83 can be greater than is used during normal operation of the discharge device 17, in order to condition them completely.

65 At station J, the next in order taken by the exhaust head 115, the upper end of the device 17 which includes the cathode assembly 19 and the adjacent portion of the exhaust tube 20 are carried into the oven 119, shown in connection with Fig. 9, which anneals and preheats these parts. No electrical connections are made to the discharge device 17 at this station. The oven 119

consists essentially of outside and inside walls following the curvature of the path of travel of the device 17, and a split top which permits the exhaust tube 20 and hollow post 24 of the exhaust head 15 to move therethrough. Heat is furnished by a commercial type strip heater 120 attached to the inside and outside walls. The exhausting operation is also continued at this station J. The sheet 121 of heat insulating material mounted below each head 15 on the arm 122 extending from the turret 16 protects the exhaust port 23 from the heat of the ovens 60 and 119.

The heating and exhausting operations are continued at the next three stations and the heating alone is continued through station K. The heat is furnished by portions of the oven 119 located at these stations whereas the exhausting operation differs somewhat from that performed at earlier stations, the result of different connections made through the rotary valve 39. At these three stations, the mercury pumps 123 which are mounted as a single unit 124 below the turret 16 on the frame as indicated are caused to assist the exhausting operation.

At station K, the lamp device 17 is provided with a second quantity of mercury, the first having been drawn out by the exhaust operations, and a specific amount of gas filling to give the lamp the proper characteristics. The mercury is introduced first by again operating the dispenser 90 attached to the exhaust port 23, this time by a solenoid 125 corresponding to the solenoid 91 at station H which is energized by operation of the switch 126 (Fig. 1) and switch 127 (Fig. 5). The switch 126 functions in a like manner to switch 103 already described, whereas switch 127 is operated by the cam 128 on the shaft 129 on the opposite side of the machine from the drive shaft 70 to which it is coupled by the chain 130 and sprockets 131 and 132. The vertical adjustment of the solenoid 125 bringing it to and from operative relation to the dispenser 90 is brought about through the cam 133 on the shaft 129 and the lever 134 which engages said cam 133 through the roller 135 and the supporting rod 136 for said solenoid 125 through the links 137. As shown, the lower end of rod 136, the links 137 and the adjacent end of the lever 134 move in the hollow interior of the standard 138. A second switch 139 actuated by the cam 140 on shaft 129 controls the period the electric valve 141 is open and therefore the amount of gas admitted into the passage in the lower section 41 of the rotary valve 39 from the source 142. The source 142 is kept at constant pressure to assure uniform amounts of gas being admitted at all times. By admitting the gas after the mercury, any stray beads of mercury which have become lodged in the exhaust port 23 or the exhaust tube 20 are carried into said device 17 with the gas.

The movement of the exhaust port 23 to the next station, L, causes the exhaust passage thereto to be sealed off in the rotary valve 39 and carries the device 17 clear of the oven 119 and into operating range of the tipping means 143. The passage in the upper section 40 of the rotary valve 39 which is part of the exhaust passage to this exhaust port 23 is at this time carried over a solid portion of the lower section 41 thereof.

The tipping means 143 is shown in Figs. 1, 8, 9 and 10, and during the indexing movement is located outward from the path of movement of the device 17. Immediately after the device 17 comes to rest, the guide 144, the burners 145—145 and the guard 146 which make up the essential

parts thereof, and which are located adjacent an intermediate portion of the exhaust tube 20, are moved in about said exhaust tube 20 and then are lowered to the operating position shown. The 5 guide 144, the burners 145—145 and the guard 146 are all mounted on the block 147 on the inner end of the pipe 148 which is mounted on the slide 149 through means permitting a limited amount of sideward as well as vertical readjustment of 10 said parts to properly align and position them with respect to each exhaust tube 20 and discharge device 17 taking this station. The vertical adjustment is allowed by the pins on the opposite sides of the block 150 on the pipe 148 which rest in upstanding bearings on corresponding sides of 15 the yoke 151. The sideward adjustment is allowed by the pivot (not shown) extending into the yoke 151 from the block 152 mounted on the top of the slide 149 and is limited by the turning 20 moment of said yoke 151 before it strikes the upstanding flange 153 (Fig. 9) on the block 152.

The forward motion of the tipping means 143, the first to occur, results from an upward movement of the rod 154 which shifts the slide 149 to 25 which it is connected by the link 155 in the bracket 156 and which is produced by lever 157 (Fig. 5). The lever 157, as shown, engages the lower end of the rod 154 which emerges from the support tube 158 for the bracket 156 and engages 30 the cam 159 on the shaft 129 through the roller 160. The connection between rod 154 and the lever 157 is made by the links 161 which engage the loose collar 162 between the fixed collars 163 on said rod 154. In the forward movement, the 35 exhaust tube 20 either passes directly into the slot 164 in the guide 144 or engages the flared open end thereof which causes the tipping means to shift position until the exhaust tube 20 falls therein. Said exhaust tube 20 also enters the 40 V-notch formed by the two portions of the guard 146 which are pivoted on the screw 165 and which separate until the said exhaust tube 20 enters the opening 166 therein. Normally both portions of the guard 146 are kept together by the spring 167 connecting their outermost ends.

The downward movement of the tipping means 143 results from a corresponding movement of the bracket 156 and the support tube 158 and carries the guard 146 against the seal 168 of the device 50 17 at which time the burners 145—145 are at the proper operation relation therewith. The support tube 158 extends downward through an arm (not shown) and the plate 169 extending from standard 138 which position it laterally and is 55 constantly under the influence of the upward expanding force of the spring 170 which is located between plate 169 and the fixed collar 171 on the support tube 158. Any change in position of the tube 158 results from a change in the cam 60 172 which change is transferred thereto through the roller 173, the lever 174, the links 175, the loose collar 176 and the fixed collars 177. Both levers 157 and 174 are pivoted on studs extending from the arm 178 on the frame (not shown).

65 All downward movement of the tipping means 143 after the guard 146 engages the device 17 is absorbed by rotation of said tipping means on pins extending from the block 150 and is against the expanding force of the spring 179 which engages the arm 180 extending from the yoke 181 and the yoke 181 engaging the pipe connection 182. The connecting arm of the yoke 181 passes through the spring 179 and slides in an opening in the arm 180. In the downward movement, the flared inner portion 146' of the guard 146

is carried into the hollow interior of the vitreous stem 183 so as to protect said stem 183 from the heat of the downwardly and inwardly directed fires from the burners 145 which are now concentrated on a very limited area of the exhaust tube 20 therein.

The combustible gas mixture is conducted to the burners 145—145 from the control valves 184 and 185 which are in turn connected to the sources of the gases through flexible rubber hoses 10 and which discharge said gases into a common passage in the connection 182, the pipe 148 and branch passages leading to said burners 145—145 in the block 147. The exhaust tube 20 is quickly softened by the fires, as it still retains most of the heat received in the oven 119, and it flows together to seal off the passage therein before the tipping means again moves down. In the downward movement, the tipping means is tilted until the block 150 rests on the yoke 151 whereupon it and the device 17 are moved down. The device 17 slides in the jaws 21—22 and 21'—22' during this period. The purpose of this final movement of said tipping means is to stretch the fused portion of said exhaust tube 20 so that 15 the fires sever the said tube 20 and tip it off. The heated and semi-annealed condition of the stem 183 and seal 168 retards any cracking and breaking thereof due to the nearness of fires from burners 145—145. Following this operation, the 20 tipping means is raised and moved outward to its rest position and the exhaust head 15 and the device 17 are carried to the next station.

The next station is M, and it and the following stations are provided to allow an operator to unload the finished device 17 from the apparatus and remove the stub of the exhaust tube 20 remaining in the exhaust port 23. When these operations have been performed, the exhaust head 15 is ready to be indexed into station 40 A and start another cycle of operation.

What I claim as new and desire to secure by Letters Patent of the United States is:

1. Apparatus for exhausting and gas filling an electric discharge device comprising a plurality of heads each including an exhaust port for receiving and making a gas-tight connection to an exhaust tube extending from the device, a dispenser mounted on said exhaust port of each of said heads and arranged to introduce a quantity of vaporizable material therein, a carrier for supporting said heads and advancing the devices through a plurality of stations in turn, valving means connected to said exhaust port and adjusted by movements of said carrier for making the exhausting and gas filling connections thereto while said device moves from station to station, and means at one of the stations for operating said dispenser to cause a quantity of the vaporizable material to be discharged into said 60 port and pass into the device.

2. Apparatus for exhausting and gas filling an electric discharge device comprising a plurality of heads each including an exhaust port for receiving and making a gas-tight connection to an exhaust tube extending from the device, a dispenser mounted on said exhaust port of each of said heads and arranged to introduce a quantity of vaporizable material therein, a carrier for supporting said heads and advancing the devices through a plurality of stations in turn, valving means connected to said exhaust port and adjusted by movements of said carrier for making the exhausting and gas filling connections thereto while said device moves from station to station, 70

5 an oven at one of said stations for heating the said discharge device all over, and means at another of said stations for operating said dispenser to cause a quantity of the vaporizable material to be discharged into said port and pass into the device.

3. Apparatus for exhausting and gas filling an electric discharge device comprising an exhaust port for receiving and making a gas-tight connection to an exhaust tube extending from the device, a carrier for supporting said exhaust port and advancing the device through a plurality of stations in turn, means arranged in position to be engaged by leads extending from the device at one of the exhaust stations for making electrical connections thereto and causing operating conditions to be established therein during exhaust, means for introducing a quantity of vaporizable material into said device at said station to cause it to operate, means at a station following the exhaust stations for again causing the introduction of a quantity of vaporizable material into said device to replace that drawn out during exhaust, and means at a succeeding station for tipping off the exhaust tube to seal the device.

4. Apparatus for exhausting and gas filling an electric discharge device comprising an exhaust port arranged to receive and make a gas-tight connection from below to an exhaust tube extending upwardly from the device, a dispenser mounted on said exhaust port and arranged to introduce a quantity of a vaporizable substance therein, a carrier for supporting said exhaust port and advancing the device through a plurality of stations in turn, valving means connected to said exhaust port and adjusted by movements of said carrier for making the exhaust and gas filling connections thereto while said device moves from station to station and means at one of the stations for operating said dispenser to cause a quantity of the vaporizable material to be discharged into said port and thence fall by gravity through said exhaust tube into the device.

5. Apparatus for exhausting and gas filling an electric discharge device comprising a movable carrier, a plurality of heads on said carrier each comprising an exhaust port for receiving and making a gas-tight connection to an exhaust tube extending from the device, a mercury dispenser mounted on each of said heads and arranged to introduce a quantity of mercury through the associated exhaust port into the associated discharge device, cam means for closing off said exhaust port in case a leaky discharge device or no discharge device at all is carried thereby, means at one of the stations taken by said heads for operating said dispenser to discharge a quantity of mercury into the associated discharge device, and means controlled by said cam means for rendering the said dispenser inoperative when said cam means is in a position closing off said exhaust port.

6. Apparatus for exhausting and gas filling an electric discharge device comprising a movable carrier, a plurality of heads on said carrier each comprising an exhaust port for receiving and making a gas-tight connection from below to an exhaust tube extending from the device, an enclosed mercury dispenser mounted on each of said heads above the exhaust port and arranged to introduce a quantity of mercury through the associated exhaust port into the associated discharge device, means connecting both said dispenser and said exhaust port to a source of vacuum, cam means for closing off said exhaust

port in case a leaky discharge device or no discharge device at all is carried thereby, means at one of the stations taken by said heads for operating said dispenser to discharge a quantity of mercury into the associated discharge device, and means controlled by said cam means for rendering the said dispenser inoperative when said cam means is in a position closing off said exhaust port.

7. Apparatus for exhausting and gas filling an electric discharge device comprising a movable carrier, a plurality of heads on said carrier each comprising an exhaust port for receiving and making a gas-tight connection from below to an exhaust tube extending upwardly from the discharge device, a mercury dispenser mounted on each of said heads above its exhaust port and arranged to introduce a quantity of mercury therein, valving means connected to the said exhaust ports and adjusted by movements of said carrier to make the exhaust and gas filling connections thereto while said heads are moved from station to station by said carrier, an oven surrounding the path of movement of the discharge devices and adapted to heat them all over while they are being exhausted, contact means arranged in position to be engaged by leads extending from each of said discharge devices for making electrical connections thereto to heat the electrodes of said device and thereby activate them during exhaust, means for subsequently causing a quantity of mercury to be delivered from the dispenser into the associated discharge device, additional contact means arranged to be engaged by the leads extending from said discharge device to cause a discharge to be initiated between the electrodes thereof, means at a station following the exhausting stations for again causing the dispenser to deliver a quantity of mercury to the associated discharge device, and

means at a subsequent station for tipping off the exhaust tube to seal the discharge device.

8. Apparatus for exhausting and gas filling an electric discharge device comprising a movable carrier, a plurality of heads on said carrier each comprising an exhaust port for receiving and making a gas-tight connection from below to an exhaust tube extending upwardly from the discharge device, a mercury dispenser mounted on each of said heads above its exhaust port and arranged to introduce a quantity of mercury therein, valving means connected to the said exhaust ports and adjusted by movements of said carrier to make the exhaust and gas filling connections thereto while said heads are moved from station to station by said carrier, an oven surrounding the path of movement of the discharge devices and adapted to heat them all over while they are being exhausted, contact means arranged in position to be engaged by leads extending from each of said discharge devices for making electrical connections thereto to heat the electrodes of said device and thereby activate them during exhaust, means for subsequently causing a quantity of mercury to be delivered from the dispenser into the associated discharge device, additional contact means arranged to be engaged by the leads extending from said discharge device to cause a discharge to be initiated between the electrodes thereof, a second oven surrounding the path of movement of the upper portion of each of the discharge devices to anneal and preheat the adjacent parts thereof, means at a station following the exhausting stations for again causing the dispenser to deliver a quantity of mercury to the associated discharge device, and means at a subsequent station for tipping off the exhaust tube to seal the discharge device.
